UNITED STATES PATENT OFFICE.

ANTHONY SNIEGOCKI, OF SAN FRANCISCO, CALIFORNIA.

DEVICE FOR CUTTING COAT-SLEEVE PATTERNS.

Application filed November 25, 1925. Serial No. 71,275.

This invention relates to a device for laying out coat sleeve patterns.

It is the principal object of the present invention to provide a generally improved device of the character referred to which is capable of adjustment so that it may be adapted for use in laying out coat sleeve patterns of any desired size, and which will form a coat sleeve pattern in perfect proportion throughout, regardless of the dimension of the sleeve.

In carrying out this object I provide a device including upper and forearm sections which are pivotally and slidably connected so that they may be relatively adjusted to form a sleeve of any desired length. An elbow section is also connected with the sections previously mentioned for cooperation therewith. So that the patterns formed by the device will unite perfectly with an arm-hole in a coat, a plurality of armhole templates are mounted on the device in a manner whereby any selected one may be easily placed in cooperative position relative to the different arm sections. The device is capable of fully laying the patterns for both the uppersleeve and the innersleeve simultaneously.

One form which the invention may assume is exemplified in the following description and illustrated by way of example in the accompanying drawings, in which:

Fig. 1 is a view of the device showing the manner in which the armhole templates are arranged relative to the upperarm section in readiness for use.

Fig. 2 is a diagrammatical view illustrating the use of the device.

Referring more particularly to the accompanying drawings, 10 indicates a device for laying out coat sleeve patterns. The device comprises an upperarm section 11, a forearm section 12 and an elbow section 14. These sections are slidably and pivotally connected so that the forearm section may be extended relative to the upperarm section in forming sleeve patterns for different lengths of sleeves.

Reference being had to Fig. 1 it will be noted that the elbow section 14 is pivotally connected as at 15 to the upper arm section 11. The other end of the elbow section is fitted with a guide pin 16 which extends through a slot 17 formed in the forearm section 12. This connection between the forearm section 12 and the elbow section 14 per-

mits sliding and pivotal movement between the forearm section and the elbow section. The cut of the cuff portion of the forearm section is such that the cuff will be flared, 60 and for this reason the guide pin 16 is positioned so that the flare of the cuff will always commence at approximately the same place relative to the elbow section and will regulate the length of the flare so that it will 65 be in perfect proportion to the length of the sleeve.

At the opposite side of the device, the forearm and upperarm sections are formed with longitudinal slots 18 through which a guide 70 pin 19 extends. This guide pin is formed with collars arranged on opposite sides of the device so that the forearm and upperarm portions of the device may slide relative to each other. The guide pin is fitted with 75 a clamping nut as is the guide pin 16 so that the sections of the device may be clamped together after they have been relatively adjusted to suit the user.

Pivotedly mounted as at 20 on the upperarm section are a plurality of armhole templates 21 which are arranged in progressively increasing sizes as indicated on the drawings. These templates are formed with a centering hole 22 which may be engaged 85 with a centering pin 23 fixed to the upperarm portion. This pin projects upwardly to engage the holes 22 and maintain the templates in position on the upperarm section. The centering pin 23 is provided with a nut 90 24 to clamp the templates on the centering pin. When the nut 24 is removed, a selected one of the templates may be swung to operative position as indicated in Fig. 2 relative to the upperarm section 11. To maintain this selected template in proper position relative to the upperarm section, the templates are each formed with an aligning opening 25 which may be engaged by an aligning pin 26 fixed on the upper arm portion. 95

To determine the length of the sleeve, a scale 27 is formed on the upperarm section adjacent its lower end. This scale cooperates with an indicating mark 28 on the forearm section. By loosening the nuts on the pins 16 and 19, the forearm section may be adjusted relative to the upperarm section. If it is desired to make the sleeve 18 inches in length when finished, the forearm section 100 is adjusted relatively to the upperarm section until the indicating mark 28 registers 105 110

with the numeral 18 on the scale. The nuts on the pins 16 and 19 may then be clamped to hold the parts in adjusted position.

To give the sleeve the proper curvature regardless of its length, the upper and forearm sections are formed with indicating lines 29 which should constantly be maintained in alignment. When these lines are in alignment, the upper and forearm sections of the device will be relatively arranged to give the proper curvature to the sleeve.

In laying out a pattern by using my improved device, if the circumference of the sleeve at its upper end, which is supposed to equal that of the armhole in the coat is 18 inches, the armhole template which is 18 inches in circumference is swung to operative position and there maintained by means of the aligning pin 26.

Adjacent the upper and outer edges of the upperarm pattern, a series of openings 30 are formed which are spaced equal distances apart laterally of the upperarm section and are arranged a proper distance from the inner edge 31 of the upperarm section so as to indicate the proper point to cut the goods to obtain a width of sleeve corresponding with the armhole opening. For example, should the armhole be 18 inches in circumference, a mark made on the pattern material through the opening adjacent the numeral 18 on the scale 30 will provide a width of sleeve properly proportionate to the armhole. It should be stated that the numerals adjacent the openings 30 indicate inches. The numeral of each hole indicate twice the distance in inches between the inner edge of the upperarm section and the hole. This is due to the fact that a double thickness of material is used to form the sleeve.

To determine the diameter of the lower or cuff end of the sleeve, a scale 32 is provided at the lower end of the forearm section. The circumference of the cuff of the sleeve may be determined by marking on the pattern at any point along this scale. Each inch on the scale is numbered twice its value due to the fact that a double thickness of goods is cut to make the sleeve.

In operation of the device, a double thickness of pattern paper is laid flat and my improved device is placed thereon. If the armhole is 18 inches in circumference, the 18 inch armhole template is chosen and arranged in proper relative position on the upperarm section 11. The forearm section 12 is then adjusted relative to the upperarm section or until the indicating mark 28 registers with the dimension on the scale 27 corresponding with the length of sleeve desired. The device is then held firmly on the paper and a mark is made on the pattern paper adjacent the dimension on the scale 32 corresponding with the circumference of cuff

desired. A line is then traced along the lower edge of the forearm portion and along the inner edge presented by the combined upper and forearm sections or the edge 31. This line is continued around the positioned 70 armhole template. The inner edge 33 of the template defining the upper end of the undersleeve pattern, the outer edge 34 of the armhole template defining the upper end of the uppersleeve pattern. 75

It will be noticed that at its outer end, the armhole template is formed with a notch 35. The outer extremity of this notch defines the outer edge of the undersleeve, while the extreme end 36 of the template defines the outer 80 edge of the uppersleeve pattern. A mark is then made through the proper opening 30 corresponding to the dimension of the armhole pattern.

To give sectional lines for joining the 85 sleeve parts after they are cut, I provide openings 37 adjacent the upper end of the upperarm section 11. I also provide similar openings 38 adjacent the cuff of the sleeve for giving a line showing the finished length 90 of the cuff. The material beyond these latter openings being the portion turned in when the sleeve is finished.

An additional opening 39 is formed adjacent the cuff. This opening 39 and the inner 95 opening 37 adjacent the upper end of the device being spaced equal distances from the inner edge 31 of the device so that a line may be drawn on the pattern intersecting these points to define the pressing line of the sleeve 100 when finished.

To give a central section line exactly at the center of the sleeve or elbow thereof, the upper and forearm sections are formed with cross slots 40 adjacent the inner edge 31. 105

Adjacent the outer edge the ends of the respective section are cutaway to form a crotch. In alignment with this crotch, the elbow section 14 is formed with an opening so that a mark may be made in the crotch. 110 A line drawn between marks made in the opening formed by the cross slots 40 and in the crotch 41 will be a central center line through the sleeve exactly half-way between the cuff and the upper end of the sleeve 115 which is indicated by a notch 42. A mark on the pattern is also made at this notch to give a point defining the upper end of the sleeve.

When the pattern has thus been marked it 120 will appear substantially as shown in Fig. 2. The lower end edge of the device is employed as a straight edge to draw a line intersecting the dots 38^a formed through the openings 38, which line indicates the end 125 of the cuff when finished. Similar lines are also formed which intersect the marks 41^a made through the crotch 41 and the cross slots 40, and a third line intersecting the dots 37^b formed through the openings 37. 130

and 37^a. The outer edge of the pattern is then used to draw a line from the point A to the point B which intersects with the dot C made through the opening 30. A second line is then drawn by the use of the outer edge of the elbow and upperarm sections from a point on the line just previously drawn where it is intersected by the elbow center line to the point indicated at D which is marked from the notch 35 on the armhole template. This gives a correct line defining the outer edge of the undersleeve. The inner edge 31 of the combined upper and forearm sections is then utilized while drawing a line through the points E and F. The point E being marked through the lower opening 38, the point F being indicated at the termination of the curved edge 33 of the armhole template.

20 The patterns thus laid out may then be cut. These patterns will be of sufficient size to allow for seams at their joining edges and for a hem at the cuff. It will be noticed that the undersleeve pattern is smaller than the 25 uppersleeve pattern, this being due to the fact that it is not desired to have the seams on the crease which is ultimately formed when the sleeve is pressed. This crease line may be drawn through the points G, H and 30 J. The points G and H being indicated by marks made through the openings 39 and 37^a, the point J being indicated by marking through the notch 42. The material between this line and the inner edge of the 35 uppersleeve pattern is folded over to unite with the undersleeve pattern, sufficient material being provided to allow for a seam. When the under and uppersleeve are joined and sewed together, the diameter of the uppersleeve will be exactly 18 inches or that 40 which is selected in commencing the pattern. Likewise the cuff will be of a diameter corresponding to the dimension on the scale 32 at which the mark A is made.

45 When cutting the pattern, the points where the sectional lines intersect the defining edges of the pattern, V-shaped notches are cut. When sewing the sleeve these notches permit the edges to be properly 50 aligned so that the sleeve will be correctly shaped.

55 It is manifest from the foregoing that by the use of my present device, a sleeve of any dimension may be quickly and properly laid out and cut. Also that a sleeve laid out by the use of the present device will be properly shaped in perfect proportion and the inner and outer sleeve portions may be correctly 60 united to form a properly shaped sleeve.

65 While I have shown the preferred form of my invention, it is to be understood that various changes in its construction may be made without departing from the spirit of the invention as defined in the appended

Having thus described my invention, what I claim and desire to secure by Letters Patent is:—

1. A device for forming coat sleeve patterns comprising an upperarm section, a 70 forearm section, connections between the forearm section and the upperarm section whereby they may be relatively adjusted to form a sleeve pattern of a desired length, said upperarm and forearm sections being 75 provided with graduations for defining the width of a sleeve, and armhole templates pivotally mounted on the upperarm section, and means whereby a selected armhole template may be placed in a correct position 80 relative to the upperarm section to cooperate therewith in forming a sleeve pattern.

2. A device for forming coat sleeve patterns comprising an upperarm section, a 85 forearm section pivotally and slidably connected to the upperarm section whereby they may be relatively adjusted to form a pattern for a sleeve of a desired length, and armhole templates of progressively increasing 90 sizes pivotally connected to the upperarm section, and means whereby a desired armhole template may be placed and held in a correct position relative to the upperarm section for cooperation therewith in forming 95 a sleeve pattern.

3. A device for forming coat sleeve patterns comprising an upperarm section, a forearm section, an elbow section, connections between said sections whereby the device may be extended to form a pattern for 100 a sleeve of a desired length, said connections maintaining the sections in desired relative positions regardless of their adjusted positions, said upperarm and forearm sections being provided with graduations for defining the width of the sleeve, and armhole templates pivotally connected to the upperarm sections and adapted to be swung to an operative position relative to the upperarm section to cooperate therewith in forming a 105 sleeve pattern, means for correctly aligning the templates relative to the forearm section.

4. A device for forming coat sleeve patterns comprising an upperarm section, a forearm section, an elbow section, connections between said sections whereby the device may be extended to form a sleeve pattern of a desired length, means for correctly aligning said sections to form a sleeve pattern of correct shape relative to its length, 115 said forearm section and upperarm section being provided with graduations for defining the width of the sleeve pattern, and armhole templates pivotally connected to the upperarm section and adapted to be disposed and held in correct operative position relative to the upperarm section.

5. A device for forming coat sleeve patterns comprising an upperarm section, a 120 forearm section, an elbow section, connec- 125

tions between said sections whereby the device may be extended to form a sleeve pattern of a desired length, means for correctly aligning said sections to form a sleeve pattern of correct shape relative to its length, said forearm section and upperarm section being provided with graduations for defining the width of the sleeve pattern, and arm-

hole templates pivotally connected to the upperarm section and adapted to be disposed and held in correct operative position relative to the upperarm section, and means for locating the sectional lines of the sleeve pattern in their correct positions. ¹⁰

ANTHONY SNIEGOCKI.
